UNITED STATES PATENT OFFICE

122,606

DESIGN FOR A WEDGE HEEL

William H. Nutt, Beverly, Mass., assignor to
United Shoe Machinery Corporation, Flemington, N. J., a corporation of New Jersey

Application August 7, 1940, Serial No. 94,281

Term of patent 14 years

To all whom it may concern:

Be it known that I, William H. Nutt, a citizen of the United States, residing at Beverly, in the county of Essex and Commonwealth of Massachusetts, have invented a new, original, and ornamental Design for Wedge Heels, of which the following is a specification, reference being had to the accompanying drawing, forming part thereof.

In the drawing:

Fig. 1 is a view, in side elevation, of a wedge heel showing my new design;

Fig. 2 is a perspective view of the heel showing it as it appears from a point of observation located above and forwardly of the heel; and

Fig. 3 is a perspective view of the heel showing it as it appears from a point of observation located below and rearwardly of the heel.

I claim:

The ornamental design for a wedge heel, substantially as shown and described.

WILLIAM H. NUTT.
